MAURICE C. HULL, OF NEW YORK, N. Y.

Letters Patent No. 62,270, dated February 19, 1867.

IMPROVEMENT IN COOKING RANGES.

The Schedule referred to in these Letters Patent and making part of the same.

TO ALL WHOM IT MAY CONCERN:

Be it known that I, MAURICE C. HULL, of the city and State of New York, have invented, made, and applied to use, a certain new and useful Improvement in Cooking Ranges; and I do hereby declare the following to be a full, clear, and exact description of the said invention, reference being had to the annexed drawings, making part of this specification, wherein—

Figure 1 is vertical longitudinal section.

Figures 2 and 3 are vertical transverse sections at the lines *x x* and *y y*, respectively.

Figure 4 is a sectional plan at the line *z z*; and

Figure 5 is a sectional plan at the line *w w*.

Similar marks of reference denote the same parts.

The object of my invention is to obtain a range having an elevated oven that will also heat a current of air circulating through the range, and around the fire-pot and ash-pit, and thence passing through an air tube to heat any chamber or room. In Letters Patent granted to me November 14, 1865, a cooking range is shown having a hot-air space around the fire-pot, but with this range there is not an elevated oven. My said invention relates to a range or stove having an elevated oven, and consists in descending smoke flues in the main portion of the range for heating a space through which the atmosphere circulates and is heated, in combination with ascending flues and an elevated oven. And I also arrange the flues so that the heat may act more uniformly upon the elevated oven. By this construction I am able to employ the range partially or wholly for heating the room or rooms, for cooking, or for baking.

In the drawing, *a a* are the side plates, *b* the back plate, *c* the front plate of a range or cooking stove, that may be set in brick-work or not, as desired; *d* is the grate in the fire-pot *e*; *f* is the ash-pit; *g* the water-back, to which water is supplied as usual by pipes, so as to heat the water in an adjacent boiler. The upper portion of the fire-pot *e* is formed as a groove, *l*, around below the water-back *g*, opening to holes through the front plate *c* of the range, and notches or openings are provided at the inner edges of this groove, so that the air passing in may enter the fire at or near its surface, and promote a more perfect combustion of the gases evolved from the fuel. The top plate *h* of the range is formed with the usual openings for receiving cooking utensils, and the plate *h'*, that is at the level of the top of the fire-pot, extends to the descending plates *k k*, so that the products of combustion pass down the flues *i i*, (between *h* and *a*), thence into the flue *l*, below the plate *l'*, and up the flue pipes *m m*, as indicated by the red arrows, to the flues *n n*, communicating with the elevated oven; or, if a direct draught is required, it may be obtained by drawing the dampers *n¹ n¹* in the division between the top plate *h* and plate *h'*. The supply of atmosphere to be heated passes in through an opening at *b¹* in the back plate *c*, into the space *c²*, thence passes forward and in contact with the casing of the ash-pit and beneath the plate *c¹*, thence rises through the opening left between the edge of *c¹* and the front plate *c*, (see fig. 4,) into the space *c³*, and returns towards the back of the range in contact with the fire-pot, and rises to the flues *o* and *o'* to the box containing the elevated oven or ovens. *p* is the case of the elevated ovens *q q*, there being spaces all around the ovens *q*, between them and the case *p*. The hot-air flues *o* open into a space, *r*, between the ovens *q q*, and the air passes also at the back of them, (see figs. 3 and 5;) the plates *r¹* and *r²* being provided, separate the hot-air and smoke spaces. *s s* are the pipes for heated air leading to the room above. The blue arrows indicate the direction of the heated air. The smoke flues *n* may be fitted with dampers, *g*, and said flue *n* opens into the spaces *s¹* below the ovens *q*, and the products of combustion pass off through the flues *4*, at the sides, and *5* at the top of the ovens, and thence by the pipe *6* to the chimney. I provide a slide or damper, *t*, through which steam and fumes from the cooking are allowed to pass to the pipe *t'*, and so escape to the chimney. I provide a flue, *u*, and damper, allowing the dust that may be in the air of the ash-pit, when the fire is raked, to pass to the flue *l*, and not come out into the room. The flues *m m* might be placed centrally of the range and the hot-air flues *o*, and smoke flues *n n* be transposed in their position if desired, and each descending flue *i* may be separated by vertical partitions, or be formed of several descending flues or pipes either at the sides or back of the range. I introduce a shallow vessel, *9*, for water, behind the flues *n* and *o*, and provide a vapor-tube, *10*, opening into the air space *r*, and a movable cap, *11*, to allow the vessel to be filled with facility. The vapors mingle with the air and moisten it.

What I claim, and desire to secure by Letters Patent, is—

1. The descending flue or flues i i , in combination with the air-heating spaces c^2 and c^3 , and flues m , passing to an elevated oven, substantially as specified.
2. I claim the arrangement of the flues i i , l , and m , for the products of combustion, in combination with the air-heating spaces c^2 and c^3 , and air flues o o^1 , as and for the purposes specified.
3. I claim the arrangement of the air flues r s , and smoke flues s^1 , 4, and 5, in combination with the elevated oven g , substantially as specified.
4. I claim the escape-damper t , and pipe t^1 , for the fumes from cooking, in combination with the elevated oven g , as set forth.
5. I claim the water vessel 9 , fitted as specified in combination with the air spaces n n and o^1 , and elevated oven range, as set forth.
6. I claim a recess or groove between the water-back and fire-pot, with openings to supply air to the fire, as and for the purposes specified.

In witness whereof I have hereunto set my signature this seventeenth day of December, A. D. 1866.

M. C. HULL.
